United States Patent Office.

ANDREW ROGERS, OF WORCESTER, MASSACHUSETTS.

Letters Patent No. 97,316, dated November 30, 1869.

IMPROVED SNOW-GUARD FOR ROOFS.

The Schedule referred to in these Letters Patent and making part of the same.

Know all men by these presents:

That I, ANDREW ROGERS, of Worcester, in the county of Worcester, in the State of Massachusetts, have invented a new and improved Snow-Guard; and I do declare that the following is a full and exact description thereof, reference being had to the accompanying drawings, and to the letters of reference marked thereon.

The nature of my invention consists in the peculiar form and construction of the standards through which the rods that form the barrier or guard are placed, giving strength to the upright part, and an even bearing throughout the entire length of the foot.

To enable others skilled in the art to make and use my invention, I will proceed to describe its construction more fully.

In the drawings—

A represents the wrought-iron standard.

B, the rods which are placed through the-holes C.

The upright part of the standard is twisted half round at the angle D.

The foot of the standard is bent, near the centre, toward the under side, to form an offset equal to the thickness of a slate.

The standard is to be fastened to the roof-boarding or rafters by means of nails or screws E.

By the foregoing description, it will be seen that the form of the standard used in my snow-guard permits the foot of the standard to have an even bearing on the boarding and slate under its entire length, thus preventing the breakage of slate by pressure on the upright part or rods, which frequently happens where the foot of standard is straight.

The twist of the standard at the angle D prevents any ordinary pressure from breaking or bending the guard. Its simple angular form permits its being used at any distance from the eaves of the roof, as well as directly at the eaves.

What I claim therein as new and of my invention, and desire to secure by Letters Patent, is—

The standard A, formed, as described, of twisted bar, adapted to the slating and boards of the roof, and fitted with bars B B B, all as described.

ANDREW ROGERS.
